Yellow Springs, Ohio, assignors to Kwik-Speed Sales
Corporation, Westerville, Ohio, a corporation of Ohio

Filed Apr. 16, 1963, Ser. No. 74,456

Term of patent 14 years

(Cl. D90—14)

FIG. 1 is a perspective view of a pedal or similar article showing our new design;

FIG. 2 is a top plan view;

FIG. 3 is a transverse vertical sectional view taken along the line 3—3 of FIG. 2; and

FIG. 4 is an end elevational view thereof looking in the direction on the line 4—4 of FIG. 2.

The side of the pedal or similar article not shown in the drawing is identical to that shown in FIG. 1, and the bottom is substantially the same as the top.

The grid-like lines shown in FIGS. 1 and 2 represent knurled surfaces.

We claim:

The ornamental design for a pedal or similar article, substantially as shown and described.
